H. HUYARD

WINDOW SASH ATTACHMENT

Filed April 20, 1926

Attest

Patented Mar. 15, 1927.

UNITED STATES PATENT OFFICE.

HENRI HUYARD, OF SAN FRANCISCO, CALIFORNIA.

WINDOW-SASH ATTACHMENT.

Application filed April 20, 1926. Serial No. 103,313.

This invention relates to attachments for window sashes.

An object of my present invention is the provision of an attachment for window sashes whereby an upper window sash may be readily pulled down.

A further object of my invention is the provision of a window sash attachment which is simple in construction, economical to manufacture and efficient in action.

With the foregoing objects in view, together with such other objects and advantages as may subsequently appear, this invention resides in the construction and arrangement of parts hereinafter described and claimed, and illustrated in the accompanying drawing, in which:

Figure 1 is a longitudinal section of a window frame and windows including their sashes, showing in side elevation my improved attachment for the upper window sash, this view being taken on line 1—1 of Figure 2.

Figure 2 is an elevational view of the construction shown in Figure 1, and

Figure 3 is a plan view of a modification of the attachment shown in Figures 1 and 2.

Referring to the drawings for more detailed description thereof, the numeral 5 indicates a window frame in which is set an upper sash 6 and a lower sash 7. Secured to the upper part of the upper sash 6 by means of fasteners 8, are rods 9, which depend from the fastening means and which are within a person's convenient reach. The rods 9, as indicated by the numeral 12 in Figure 1, are offset so that at their lower ends they pass inside of the lower sash.

Guide means 15, secured to the lower sash, are provided as guides for the rods 9 and comprise rings through which the rods may slide. It will be readily noticed from Figure 1 that the lower portions 17 of the rods are bent outwardly from the vertical portions of the rods in order to secure a better grasp on the latter, whereby the pulling down of the upper sash is facilitated.

According to the modification shown in Figure 3, the lower ends of the rods 9 may be joined by a transverse rod 18, the end portions of which are reduced and threaded, the threaded portion threadedly engaging the inwardly turned ends of the rods 9. The transverse rod 18 is preferably disposed in its normal position above the window of the lower sash and adjacent the top of the lower sash.

While I have described one embodiment of my invention, modifications thereof may be readily devised without departing from the spirit of my invention, and it is to be understood that such modifications come within the scope of the appended claim.

I claim:

An upper window sash and spaced elongated members secured at their upper ends to said sash, said members extending downwardly adjacent the sides of said sash to within a person's convenient grasp, and a transverse bar threadedly joining the lower ends of said members, said bar being detachable from said members, a lower window sash and guide means on said lower sash for said members.

HENRI HUYARD.
